United States Patent Office.

MICAJAH CURRIER BURLEIGH, OF GREAT FALLS, NEW HAMPSHIRE.

Design No. 4,226, dated July 19, 1870.

DESIGN FOR STOVE-DOORS AND PANELS.

The Schedule referred to in these Letters Patent and making part of the same

To all whom it may concern:

Be it known that I, MICAJAH CURRIER BURLEIGH, of Great Falls, in the county of Strafford and State of New Hampshire, have invented a new and original Design for Stove-Doors and Panels; and I do hereby declare that the following is a full, clear, and exact description thereof, which will enable others skilled in the art to make and use the same, reference being had to the accompanying drawing forming part of this specification, in which—

Figure 1 is a face view of my improved design as applied to a stove-door.

Figure 2 is a cross-section of the same, taken through the line $z z$, fig. 1.

Similar letters of reference indicate corresponding parts.

My invention has for its object to furnish a new design for a stove-door or panel, which shall be neat, simple, and appropriate; and

It consists in the design herein shown and described.

A is the body of the door or panel, which is slightly convex, and has a raised star, B, in its center.

The panel is surrounded with a raised border, formed of flat or plane surfaces, D C E F, arranged at an angle with each other, as shown in the drawing.

The angles of the border, at the corners of the door or panel, may be right angles, as shown at the corners G, or they may be formed as shown at the corners H, by cutting off the corners with planes $d^1 c^1 e^1 f^1$ at the same angles with the plane of the panel or door that the plane surfaces D C E F have, and then cutting off the two angles thus formed at each corner by the planes $d^2 c^2 e^2 f^2$, as shown in the drawing.

Having thus described my invention,

I claim as new and desire to secure by Letters Patent—

The design for stove-doors and panels, substantially as herein shown and described.

MICAJAH CURRIER BURLEIGH.
